UNITED STATES PATENT OFFICE.

ROBERT A. McCARTY, OF DETROIT, MICHIGAN, ASSIGNOR OF ONE-HALF
TO GEORGE MAITLAND, OF SAME PLACE.

CASH AND PARCEL CARRIER.

SPECIFICATION forming part of Letters Patent No. 325,426, dated September 1, 1885.

Application filed May 2, 1884. (No model.)

To all whom it may concern:

Be it known that I, ROBERT A. McCARTY, of Detroit, Wayne county, Michigan, have invented a new and useful Improvement in 5 Cash and Parcel Carriers; and I hereby declare that the following is a full, clear, and exact description thereof, which will enable others skilled in the art to make and use the same, reference being had to the accompanying drawing, which forms a part of this specification.

The figure is a perspective drawing of my invention, showing the carriage employed by me, the method of holding it in position while 15 a propelling force is accumulating, and the method of releasing the carriage and allowing the accumulated propelling force to be expended in moving the carriage forward along the way upon which it is adapted to travel.

20 My invention has for its object to furnish a simple and convenient engine or motor for imparting motion to a carriage adapted to travel on a way or track extending from one portion of a building to another, particularly 25 when such carriage is used for transporting cash or parcels from that portion of a store occupied by the salesman to the cashier's or book-keeper's desk and returning the same from the cashier or book-keeper to the sales- 30 man.

The way or track employed by me consists of a strained wire, which is either horizontal or inclined. I prefer to use an inclined way, inasmuch as in that case only a single propelling-engine is necessary, as the carriage, having mounted an inclined way, in consequence 35 of force imparted to it, will return by force of gravity when allowed to do so. My carriage is shown at A, and consists of a hanging car, 40 a b, hanging from two or more wheels. Upon these wheels I place grooved rubber tires, or manufacture the wheel, except the axle upon which it turns, entirely of rubber, and in this way overcome the noise usually accompanying 45 the passage of a hanging car upon a wire way. At either end of the carriage is a hook or detent adapted to catch upon appropriate hooks fixed near either end of the way, and by the interlocking of the hook upon the end 50 of the carriage with the corresponding hook

near the end of the track the carriage is held from motion along the track until the interlocking of the hooks has been loosened. Upon the carriage is constructed a projection or horn (shown at e) rising above the plane of the 55 track, and adapted to catch the cord C, hereinafter described, and retain said cord before it as the carriage moves from the position shown by the dotted lines to the position shown in full lines. 60

My propelling-engine is placed at or near one end of the wire way W, extending from one portion of the building to another. Upon the wall or other fixed portion of the building to which an end of the wire way is attached I 55 affix standards M M', which project from the wall a short distance, and at their outer extremity support an upright rod or standard, N N', the upper end of which is slotted, and has mounted in the slot two sheaves, or a double sheave, E E'. Through a perforation in the lower part of the standard N N' I pass the wire track W, attaching the end, after passing it through such aperture, to the wall of the building. Just below the aperture through 75 which the wire W passes I mount upon the standard N N' a spring-catch, c, and a short distance above the wire way, upon the standard, I mount the U-shaped or compound arm V, the outer end of each branch of which 80 (marked B D) carries a sheave or pulley. Over these sheaves I pass a cord, passing from above at H over the sheave at B, thence so it will lie loosely on the wire way, up over the sheave at D, and back to the point H. When the 85 carriage is not present, this cord will lie loosely on the wire; but when the carriage is in the position shown at A the cord will have been caught under the horn e, and will assume the position shown in full lines. The two ends of 90 this last-mentioned cord are brought together and attached to a spring, H, which may be either rubber or coiled wire. At the other end of the spring H, I attach two other cords, passing therefrom over E and E', uniting in 95 a single cord after they have turned downward over E E'. The united cord is continued downward to O, where it is terminated by a ring or other suitable appliance to enable it to be grasped. 100

From the spring-catch *c*, I pass still another cord, which is attached to that passing from *E* to *O*. The point of attachment is determined in the following way, to wit: After the 5 wire track is mounted and the distance to be traversed by the carriage is determined, I find by experiment how much expansion of the spring *H* will be required to propel the carriage over the fixed distance, then with the 10 carriage in the position shown at *A*, with the cord *C* passing around the horn *e*, as shown in the drawing, I expand the spring *H*, by pulling downward upon the ring *O*, until the force stored in the expanded spring is sufficient to 15 propel the carriage as far or as forcibly as may be desired. The cord *X*, having one end attached to the catch *c* at *T*, is then brought downward to the cord passing from *E* to *O* and fastened. In making this attachment it is desirable to 20 make the angle between the two cords as small as possible. Upon drawing the ring *O* a short distance farther downward the expansion of the spring is increased; but the interlocked hooks *a c* are immediately disengaged and the 25 contractile force of the spring, exerted through the cord *H B C D H*, immediately propels the carriage forward. At the end *W* of the track a catch, *K*, made of spring metal, or having a leaf-spring beneath it, as shown, is fixed, 30 which interlocks with the hook on the forward end of the carriage and prevents a return until released either by hand or by suitable mechanism. The arms *V* may be attached directly to the wall; but I prefer to attach them to the 35 perpendicular rod or standard affixed to but held at a little distance from the wall, as shown in the drawing. They are thus held firmly, and at the same time may be readily adjusted at any elevation or in any desired position. 40 horizontally by means of set-screws.

I do not claim herein a cash-carrying system wherein are combined a way, a carriage adapted to move on said way, and means for giving an impetus to said carriage, or such a system 45 when such impelling device is stationary with relation to the carriage, or such a system when such impelling device is a spring or spring mechanism; and, further, I do not claim herein the employment in such a system of an impelling device at each end of the way, or a 50 horizontal way, in combination with an impelling device at each end thereof, all such features being already included in an application for patent filed by me March 1, 1884.

Having thus described my invention and its 55 mode of operation, what I claim as novel, and desire to have secured to me by Letters Patent, is—

1. In combination with a carriage adapted to travel on a way, a spring arranged near one 60 end of said way, means, substantially as described, of producing tension in said spring by drawing the same against the rear of said carriage, and a catch adapted to grasp said carriage and hold the same until the desired 65 amount of tension has been produced in said spring to project the carriage to the opposite end of the way.

2. A cash-carrier system consisting of a 70 way, a carriage adapted to travel thereon by the force of a spring apparatus, substantially as described, connections therewith in reach of the salesman for compressing said spring, and a catch for holding said carriage against the propulsive force of said spring, and a cord 75 or like connections within reach of the salesman for unclasping said catch, substantially as shown and described.

3. In an engine for propelling a carriage upon a way, the combination of a cord passing 80 from the spring of said engine across the path of the carriage, a spring attached to said cord, and a cord or like connection with said spring within reach of the operator, whereby the spring may be expanded by force applied to 85 said cord, substantially as described.

4. In an engine for propelling a carriage upon a way, and in combination a spring brought into tension by expanding the same, a cord to enable one end of said spring to hold or 90 press against said carriage, and a second cord attachment to the other end of said spring, passing over sheaves and brought downward to enable tension to be produced on said spring, substantially as and for the purposes described. 95

5. In a cash-carrying system, the combination of an inclined way, a carrier adapted to move thereon, and a projecting apparatus at the lower end of said way giving such carrier an initial impetus propelling it to the top of the 100 way, the carrier being returned by gravity, substantially as set forth.

ROBERT A. McCARTY.
